TYPEWRITING MACHINE

Burnham C. Stickney, Hillside, N. J., assignor to
 Underwood Elliott Fisher Company, New York,
 N. Y., a corporation of Delaware

Application May 4, 1933, Serial No. 669,282

23 Claims. (Cl. 197—131)

This invention relates to the art of typewriter-manifolding, and particularly to improvements in the means for collating or assembling work-sheets and interleaving or loading them with 5 carbon-sheets.

It is usual for the operator to place a work-sheet upon the desk, and deposit a carbon-sheet thereupon, and place a second work-sheet upon the carbon, and then deposit a carbon-sheet upon 10 the second work-sheet, and then place a third work-sheet upon the latter, and so on, until the requisite number of work-sheets and carbons is assembled; and then the pack is introduced into 15 the typewriting machine. After typing the page, the carbons are separated one by one from the work-sheets, and then used again for interleaving with work-sheets preparatory to typing the next page, and so on.

It is an object of the present invention to avoid 20 the labor and loss of time involved in the usual method of preparation for manifolding, as well as the usual slow picking of the sheets apart after manifolding, and also to avoid waste of carbon which occurs in many instances, as for 25 example where only a few lines are typed upon each page.

According to the present improvements, the typewriter-carriage may be provided with a sheet-loading bed, which may extend backwardly 30 from the revoluble platen usually journaled upon the carriage; the bed having a gage for the leading edges of the work-sheets, and also preferably having opposite side gages adjustable for different widths of sheets. The work-sheets may be placed one by one upon said bed, with their leading 35 edges against the main gage. It is only necessary to drop each sheet in the box, which is open at its rear.

The carbons are supplied in the form of plies 40 of webs that are preferably wound upon spools, arranged at the rear of the machine. The plies of carbon are paid off from the spools, and form fly-leaves to be swung down in alternation upon the work-sheets.

When this loading is completed, the platen 45 is depressed to typing position, and presses the interleaved work-sheets down against the bottom feed-rolls provided upon the carriage, so that the sheets are gripped by the roll and platen.

Said platen is mounted upon a swinging sub-frame. The mounting of the platen and sub-frame may be similar to that which is commonly used for different purposes in Underwood type-writing machines.

55 The swinging of the platen upwardly and for-

wardly, according to the present invention, leaves room for the carbon fly-leaves to be swung downwardly and forwardly singly upon the deposited work-sheets.

The loading box with its gages is so placed that 5 the forward ends of the work-sheets overlie the aforesaid feed-roll which normally runs upon the underside of the platen, for enabling said roll to press the forward end of the pack of sheets up against the platen, when the latter is in 10 printing position.

The platen is then rotated to bring the work-sheets forward and up to typing position. The 15 typing of the page proceeds line by line in the usual way. The fly-leaves or portions of the carbon-plies which extend rearwardly from the pack of work-sheets to the spools, are drawn forwardly as said work-sheets feed around the platen; and they pull the spools forwardly.

The spools are preferably mounted upon a forwardly-swinging frame, which is hinged at its lower portion to a support, and extends upwardly and rearwardly from its hinge to carry the spools.

After the typing of the page is completed, the platen is swung upwardly and forwardly in a 25 known manner. The pack of work-sheets is thus brought to a flat condition, and it is grasped by its forward edge and pulled forwardly out of the machine, leaving the flat carbon fly-leaves and spools undisturbed. The spools may be either 30 locked or frictionally held against accidental rotation. The spools may now be thrust rearwardly to normal position, together with the frame on which they swing; or a weak returning-spring may be employed for said spool-frame. 35

The front sheet-gage rises automatically to 40 normal position preparatory to the next carbon-loading operation, and it is dropped automatically when the platen is swung down to printing position.

Thus the operation of manifolding page after page may proceed indefinitely. As soon as a leaf of carbon becomes worn, it may be cut off and a fresh portion may be pulled from the supply-spool to serve as a new fly-leaf. Means may be 45 provided for cutting off the worn-out section of carbon-web.

The front gage may be made finely adjustable forth and back to a moderate extent, so that when the work-sheets are advanced by the rotation of 50 the platen, the first printed blank line on the work-sheet may be located accurately at the printing point, without the need of manual adjustment of the sheet.

If the manifolding is done only near the bot- 55

tom of the work-sheet, then only a corresponding short length of each carbon fly-leaf needs to be laid upon the sheet in the loading bed or box; and a hanging loop of carbon may drop between the spools and the box. This will obviate the danger of dragging or slipping back of the carbon when the work-sheets are advanced by the rotation of the platen, before the lower portion of the set of work-sheets reaches the bite of the platen and feed-roll.

The spool-frame may be hinged upon a support which itself is hinged upon the rear portion of the paper-carriage, with which the spools travel. Said support may be folded forwardly by pressing it about its point of hinging to the carriage. This will compact the device for shipment, without removing it from the typewriter. The spool-frame may also fold forwardly; and the loading box is itself hinged so that it may tip downwardly and rearwardly and assume an upright position compactly at the back of the machine. The device may readily be applied to existing Underwood machines. Various devices may be adopted for adjustably stopping the rearward movement of the spool-frame, according to the work in hand.

Other features and advantages will hereinafter appear.

In the accompany drawings,

Figure 1 is a sectional side elevation of an Underwood typewriting machine fitted with the present improvements in their preferred form, and showing the parts in normal positions subsequent to loading the work-sheets with carbons.

Figure 2 is a plan of the machine seen at Figure 1.

Figure 3 is an elevation showing the compact collapsed condition of the spool-frame, the interleaving bed, etc.

Figure 4 is a sectional side elevation showing one work-sheet having been deposited upon the bed, and the carbon-leaves being held in the hand of the operator preparatory to being dropped singly upon the work-sheets; one dropped carbon being indicated by a dot-and-dash line.

Figure 5 shows all of the work-sheets and carbon-leaves assembled or gathered.

Figure 6 shows the platen dropped upon the gathered sheets to grip the same against the feed-roll, so that the pack may be advanced by the rotation of the platen.

Figure 7 shows the position of the parts when the typing of the page is completed; the spools having been dragged to their extreme forward positions.

Figure 8 shows the platen as having been elevated to idle position, thus bringing the work-sheets and carbons to comparatively flat condition. This view also shows the work-sheets gripped by their forward edges, to be pulled away from the carbons and out of the machine; whereupon the carbon-spool frame may be returned by its spring or handle 46 to its normal position at Figure 1.

Type-bars 10 strike rearwardly against the front of a platen 11, upon a carriage 13 or the case-shifting platen-frame thereof. The carriage is provided with a letter-feeding mechanism, including a rack 14, said carriage traveling upon the usual rails 15, 16, 17. Feed-rolls 18, 19 run upon the underside of the platen, to co-operate with the latter in advancing the work-sheets. These feed-rolls may be cast off by means of a rocking cam-shaft 20 in the usual manner, if it should be desired to readjust the assembled work-

sheets while they are in position around the platen.

By means of an axle 12 the platen is journaled in a swing-frame, comprising arms 21, 22 and a transverse connecting plate 23, the latter also functioning as a paper-shelf at the delivery side of the platen. This bail-swing-frame is hinged to move upwardly and forwardly upon studs 24 which project from opposite ends 25 of the paper-carriage or of its case-shifting platen-frame. The platen 11 may be displaced upon this frame 21, 22, 23 from the full-line printing position at Figure 1 to the dotted-line position, thus leaving ample room in the paper-carriage between the ends thereof for convenience in manipulating work-sheets in the manner herein explained.

The bottom of the empty work-space in the carriage is occupied by the forward portion of a bed 26, upon which the work-sheets are deposited one by one. Their leading edges are set to a gage 27, while the latter stands in its dotted-line erect position, that is, while the platen occupies its upwardly-displaced position at 11^a. The platen is swung upon studs 24 from printing position to the dotted-line position at Figure 1 in a known manner, and remains elevated during the interleaving or loading of work-sheets and carbons.

Said paper-feed roll 19 may be located between the bed 26 and the sheet-gage 27, and the work-sheets, when presented to said gage, have their forward ends overlying said feed-roll. The latter and the feed-roll 18 project up through openings in a curved paper-guiding apron 28, which underlies the platen forwardly of the bed 26.

The operation of assembling the work-sheets and carbons begins with the deposit of the first work-sheet upon the bed 26 and against the gage 27. The sheet usually overhangs the rear end of the bed, the latter extending towards a set of carbon-web spools 29. A length of carbon is drawn off from one of the spools, to form a fly-leaf, which is dropped upon the deposited work-sheet 27^a, with the forward end of the carbon brought nearly to the gage 27 (Figure 4). Then another work-sheet is procured and dropped upon the carbon. A second carbon-leaf is brought forward, being obtained from the other spool 29; and it is dropped upon the upper work-sheet 27^a. Then a third work-sheet is dropped, covering the second carbon, and so on, alternating work-sheets with carbon-leaves, to the number desired (Figure 5).

This work of loading is expedited by opposite side gages 30 that are provided upon the bed. The three gages and the bed form a box to which the sheet fits, so that adjustment of the sheet is unnecessary. The gathered sheets overlie the main feed-roll 19.

The operator then swings the platen down from the displaced position 11^a to the printing position 11. The swing-frame 21, 22, 23 is locked down by a latch 31 in a known manner. The forward ends of the gathered sheets are gripped by the descending platen and the feed-roll 19, which may now co-operate to advance the pack of sheets and carbons around the platen to printing position (Figure 7).

The front gage 27 is automatically withdrawn from the path of the advancing sheets by means of an arm 32, which is seen to project from a gage-frame 33. The arm 32 is depressed by an elbow 32^a on the swing-frame, whereby said gage-frame 33 is turned down around its hinge 34 to 75

the Figure 1 position, with its gage lying idly below the paper-apron 28 (Figure 6).

If the work-sheets have been prepared with printed lines to receive the typing, then the working position of the gage 27 may be regulated accordingly by means of a vertical stop-screw 35, which is threaded into a boss 36 on the carriage, to be adjusted up or down. The end of the screw stands in the path of an upright stop-rod 37, whose lower end is pivoted at 38 to an arm 39 of the hinged gage-frame 33. A spring 40 serves to raise the stop-rod 37 and the sheet-gage 27 as far as they will go, when the platen is elevated at 11^a. By turning down the screw 35, the gage 27 may be finely adjusted in forward direction. This will allow the work-sheets to occupy a little higher position, so that the first line of typing may fall at the desired position on the sheet. During the typing, the platen and sheet are held by detent 39^a and wheel 39^b.

During the typing of the page, the work-sheets, together with carbons or fly-leaves 29^a and spools 29, are drawn forwardly by the rotation of the platen (Figure 7). There is a considerable reach 25 of carbon between the spools and the work-sheets at the completion of the typing of the page, for the spools may not be advanced beyond the dotted-line position seen at 29^b, Figure 1.

Each spool may be wound with a double or 30 triple ply of carbon, according to the number of work-sheets that are to be manifolded, using one ply for each work-sheet. As many spools may be provided as may be desired, and the group may be carried upon the upper end of a swing-frame 35 41, hinged at its lower forward end at 42 upon a support 43.

During the typing of the page, it may be desired to rotate the platen backwardly at times, and in such a case the slack in the carbon-plies 40 may be taken up by a light spring 44, coiled about the hinge-pintle 42.

After the typing of the page, a finger-piece 45 may withdraw the latch 31, to release the swing-frame, which then may be swung up to the dotted-line position 11^a at Figure 1. This inverts the work-table 23, which now occupies a horizontal forward position at 23^a; and the typed work-sheets may be grasped by their ends and pulled forwardly, to strip them from the carbon-leaves and spools may be returned by the spring 44, or by a suitable handle 46 connected to the spool-frame.

The carbon-spool frame is arrested by a stop-device including a slotted link 47 that connects a stud 48 of the spool-frame with a stud 49 on the fixed support 43. The link is provided with a series of slots 50, affording adjustment of the spool-frame stop, according to the kind of work 55 in hand. The stud 49 is provided with a flat swiveled block 51 fitting in a longitudinal slot 52 in the link and adapted to pass over the notches 50 during the forward stroke of the spool-frame. The parts are now in position to assemble the work-sheets with interleaved carbons, preparatory to typing the next page.

During the pulling of the carbons forwardly at the typing operation, and during the movement of the spools rearwardly at the carbon-stripping operation, the spools may be held against rotation by any suitable locking device, or by friction washers 53.

The bed 26 occupies a depressed position in the machine, as compared with the delivery table 23, and is inclined downwardly and forwardly so

that the weight of the sheet may be a factor in dropping it against the front gage 27. The table is preferably curved to correspond generally with the path of movement of the carbon-spools.

It will be perceived that the carbon-leaves may 5 be pulled forwardly from the spools and all held in one hand (Figure 4), while the other hand of the operator is used for depositing the sheets in the box; and that the operator may readily drop the under leaf of carbon upon each work-sheet, 10 so that the entire operation of assembling and passing the sheets and carbons into the bite of the platen and feed-roll is expedited. When any carbon fly-leaf becomes worn, it may be sheared off; or the machine may be provided with a carbon-shearing knife 53^a of kncwn construction, adjacent to the platen.

When only a short lower portion of each sheet is to be overlaid with the carbon-leaf, a portion 20 of the leaf may drop between the table 26 and the carbon-spool, to form a carbon-loop, and the weight of the overlying sheets will afford sufficient friction to hold the carbon-ends so that they may take up the slack in the loop as they are advanced by the work-sheets. Loops may 25 also be formed, if desired, by swinging the spool-frame forward and locking it there, even after the forward ends of the carbon fly-leaves have been set nearly up to the gage 27. For this purpose, the spool-frame 41 may be swung forwardly 30 and the stud 48 placed in a different notch 50, so that the lengthy carbon-loop will fall between the rear of the work-sheets and the spools.

Adjustment of the sheet-gathering box may be provided by forming the bed 26 in two sections, 35 26 and 26^a at Figure 2. These sections may approach or recede from each other, being held by means of screws 54 to a transverse supporting bar 55; the screws passing through adjustment-slots 56 parallel with the platen.

To prepare for shipment, the support 43 may be swung forward about its hinge 51 to occupy a pendent position at the back of the typewriting machine 58. Said hinge 51 is provided in a bracket 59, which is secured by bolts 60 to the main 45 bar 13 of the carriage. The support 43 may be held by a wing-screw 61, Figure 1, in either collapsed or extended condition. When said support is collapsed, the spool-frame 41 may be collapsed forwardly about pivot 42, and stand compactly behind the typewriter. The loading box 26 may be tipped to a compact vertical 50 position behind the typewriter; the box being for this purpose provided with legs 62, which are hinged at 63 to the upper portion of the bracket 55 59.

The brackets 59 are supported from the same fixture 64 that carries the usual tabulator-rack 65, Figure 1.

In unfolding the frames to working positions, 60 the table 26 is swung up about the hinge 63, to the position at Figure 1. Then the support 43 is swung up, and a pin 66 thereon is brought to a position beneath a pin 67 that projects from the leg 62 of the table. Then the table is permitted 65 to drop a trifle, until its pin 67 rests upon said pin 66, which affords a permanent support for the table.

The interleaving table or box 26 overlies the tie-bar 68 of the frame 25, which is the case-shift frame of the paper-carriage. Said tie-bar 70 is depressed for that purpose, below its former position.

The hinge of the platen swing-frame is coaxial with pinions 69, with each of which meshes a 75

platens-gear 70 and a companion gear 71 that is controlled by a knob 72; this being a known construction. By this means operative connection is preserved between the platen and the knobs, 5 and also between the platen and the line-space wheel 39^b, while the platen is in elevated position.

Each carbon-spool may be detachable. For example, its square shaft 73 may be reduced at 10 74, permitting the shaft to be pressed to the left (against compressive tension of spring 75) far enough to clear the right-hand end of the shaft from the side 76 of the spool-frame, permitting the spool to be withdrawn.

15 Each carbon-spool being keyed to its shaft, there is provided the light spring 75, which may be so weak as to yield readily to a sudden pull upon the frail carbon-web, thus minimizing the liability of the latter to become damaged from 20 tearing. The spring will suffice to return the spool to normal rotative position when the web is released from tension.

A length of web may be permanently pulled off from either spool, which for this purpose may 25 be provided with a friction washer 53, bearing against the inner face of the fixed plate 16, being held in frictional contact by the same spring 75. The washer is rotated by means of an arm 77 on the spool-shaft. The arm strikes a pin 78 projecting from the washer. In operation, the spring will yield to ease the pull of the web, while the washer remains stationary; but after the spool has been given an idle revolution by means 30 of the pull, the arm 77 strikes the pin 78, and 35 further, gradually increased pull on the web causes it to be paid off permanently from the spool. At this time the washer and spool rotate together. When sufficient of the web has been paid off, it is released, and the spring 75 will 40 react to the extent of say one revolution. The adjacent portion of the web rewinds upon the spool, and the spring resumes its normal function of lightly restraining the web against pull. It will be understood that the spring will yield to a light 45 pull; but the frame itself will yield to the pull of the web and rock upon its hinge 42 after the spring is tautened. The handle 46 may be grasped to hold the spool-frame steady during the pulling of a fresh length of web off from 50 either spool; said handle being pivoted at 79 to the spool-frame. The arms 41 are connected by a tie-bar 80 at their upper ends, completing the ribbon-spool frame.

Variations may be resorted to within the scope 55 of the invention, and portions of the improvements may be used without others.

Having thus described my invention, I claim:

1. In a typewriting machine, the combination 60 with a carriage, of a platen, a feed-roll to run upon the underside of the platen, means for supporting the platen upon the carriage for displacement upwardly and forwardly from the feed-roll, and a work-sheet-loading bed upon said carriage 65 and extending rearwardly from the feed-roll and platen, so that work-sheets, deposited upon said bed when the platen is displaced, are thereby presented facewise to the feed-roll, carbon-supply carriers supported in rear of said work-bed for 70 forward idle movement with the work-sheets as the platen is rotated, whereby the work-sheets may be deposited, one by one, upon the bed, and each overlaid by a carbon fly-leaf extending forwardly from a supply-carrier, and whereby the 75 platen may then be returned to printing position

and co-operate with the feed-roll to grip the deposited sheets preparatory to typing the page.

2. In a typewriting machine, the combination 5 with a carriage, of a platen, a frame for supporting the platen upon the carriage for displacement upwardly from printing position, a work-sheet-loading bed upon said carriage and extending rearwardly from the platen, so that work-sheets, deposited upon said bed when the platen is displaced, are thereby presented facewise below the platen, a gage at said bed for the leading ends of the deposited work-sheets, a carbon-supply supported in rear of said work-bed for forward idle movement with the loaded work-sheets as the platen is rotated, and means 10 to co-operate with the platen, when returned to printing position, to grip the deposited sheets preparatory to typing the page.

3. In a typewriting machine, the combination 15 with a carriage, of a platen, a frame for supporting the platen upon the carriage for displacement upwardly from printing position, a work-sheet-loading bed upon said carriage and extending rearwardly from the platen, so that work-sheets, deposited upon said bed when the 20 platen is displaced, are thereby presented facewise below the platen, a gage at said bed for the leading ends of the deposited work-sheets, a carbon-supply supported in rear of said work-bed for forward idle movement with the loaded work-sheets as the platen is rotated, and means to 25 co-operate with the platen, when returned to printing position, to grip the sheets preparatory to typing the page, said gage being depressible 30 out of the path of the sheets.

4. In a typewriting machine, the combination 35 with a carriage, of a platen, a frame for supporting the platen upon the carriage for displacement upwardly from printing position, a work-sheet-loading bed upon said carriage and 40 extending rearwardly from the platen, a gage at said bed for the leading ends of the work-sheets, a carbon-supply supported in rear of said work-bed for forward idle movement with the loaded work-sheets, means to co-operate with 45 the platen, when returned to printing position, to grip the sheets preparatory to typing the page, means to enable said platen-frame to depress said gage, and a spring to lift said gage when the platen-frame is displaced upwardly.

5. In a typewriting machine, the combination 50 with a carriage, of a revoluble platen, means for supporting the platen upon the carriage for displacement upwardly from printing position, a work-sheet-loading bed upon said carriage and 55 extending rearwardly from the platen, so that work-sheets, deposited upon said bed when the platen is displaced, are thereby presented facewise below the platen, a gage at said bed for the leading ends of the work-sheets, said bed 60 having a side gage for the work-sheets, carbon-carrying spools supported in rear of said work-bed for idle forward movement with the work-sheets when the platen is rotated, and a feed-roll disposed to underlie the deposited sheets and 65 effective when the platen is returned to printing position, to co-operate with the platen to grip the sheets preparatory to typing the page.

6. In a typewriting machine, the combination 70 with a carriage, of a platen, a frame for supporting the platen upon the carriage for displacement upwardly from printing position, a work-sheet-loading bed upon said carriage and 75 extending rearwardly from the platen, so that work-sheets, deposited upon said bed when the

- 5 platen is displaced, are thereby presented face-
wise below the platen, a gage at said bed for
the leading ends of the work-sheets, a carbon-
supply supported in rear of said work-bed for
5 forward idle movement with the loaded work-
sheets when the platen is rotated, and means to
co-operate with the platen, when returned to
printing position, to grip the sheets preparatory
to typing the page, said gage being compressible
10 out of the path of the sheets, said bed having
opposite side gages for the work-sheets, the bed
and leading gage and side gages forming a box
to fit the sheets.
7. In a typewriting machine, the combination
15 with a carriage, of a platen, a frame for sup-
porting the platen upon the carriage for dis-
placement upwardly from printing position, a
work-sheet-loading bed upon said carriage and
extending rearwardly from the platen, so that
20 work-sheets, deposited upon said bed when
the platen is displaced, are thereby presented face-
wise below the platen, a gage at said bed for the
leading ends of the work-sheets, a carbon-supply
supported in rear of said work-bed for forward
25 idle movement with the loaded work-sheets when
the platen is rotated, and means to co-operate
with the platen, when returned to printing po-
sition, to grip the sheets preparatory to typing
the page, said gage being compressible out of the
30 path of the sheets, said bed having opposite side
gages for the work-sheets, the bed and leading
gage and side gages forming a box to fit the
sheets, said side gages being relatively adjust-
able.
- 35 8. In a typewriting machine, the combination
with a carriage, of a platen, a frame for sup-
porting the platen upon the carriage for dis-
placement upwardly from printing position, a
work-sheet-loading bed upon said carriage and
40 extending rearwardly from the platen, so that
work-sheets, deposited upon said bed when
the platen is displaced, are thereby presented face-
wise below the platen, a gage at said bed for the
leading ends of the work-sheets, a carbon-
45 supply supported in rear of said work-bed for
forward idle movement with the loaded work-
sheets, means to co-operate with the platen,
when returned to printing position, to grip the
sheets preparatory to typing the page, said page
50 being compressible out of the path of the sheets,
and means for adjusting said leading-edge gage
forwardly and backwardly.
9. In a typewriting machine, the combination
55 with a carriage, of a platen, a frame for support-
ing the platen upon the carriage for displace-
ment upwardly from printing position, a work-
sheet-loading bed upon said carriage and ex-
tending rearwardly from the platen, so that work-
60 sheets, deposited upon said bed when the platen
is displaced, are thereby presented facewise be-
low the platen, a gage at said bed for the leading
ends of the work-sheets, a carbon-supply sup-
ported in rear of said work-bed for forward
65 idle movement with the loaded work-sheets when
the platen is rotated, and means to co-operate
with the platen, when returned to printing po-
sition, to grip the sheets preparatory to typing
the page, said gage being compressible out of the
70 path of the sheets, said bed having opposite side
gages for the work-sheets, the bed and leading
gage and side gages forming a box to fit the sheets,
said bed being formed in two side sections, each
carrying one side gage, and said carriage having
75 means whereon said sections are mounted for

relative adjustment to accommodate different
widths of sheets.

10. In a typewriting machine, the combination
with a carriage, of a revoluble platen, means for
supporting the platen upon the carriage for dis-
placement upwardly from printing position, a
work-sheet-loading bed upon said carriage and
extending rearwardly from the platen, so that
work-sheets, deposited upon said bed when the
platen is displaced, are thereby presented face-
wise below the platen, a gage at said bed for the
leading ends of the work-sheets, carbon-carrying
spools supported in rear of said work-bed, a feed-
roll effective when the platen is returned to print-
ing position, to co-operate with the platen to 15
grip the sheets preparatory to typing the page,
and a forwardly-swinging frame whereon said
spools are mounted to move forwardly with the
loaded work-sheets when the plane is rotated,
said frame hinged upon a support which extends 20
down from said carriage, the spool-frame ex-
tending upwardly and rearwardly from its hinge
and carrying the spools at its upper end.

11. In a typewriting machine, the combination
with a carriage, of a revoluble platen, means for
supporting the platen upon the carriage for dis-
placement upwardly from printing position, a
work-sheet-loading bed upon said carriage and
extending rearwardly from the platen, so that
work-sheets, deposited upon said bed when the
platen is displaced, are thereby presented face-
wise below the platen, a gage at said bed for the
leading ends of the work-sheets, carbon-carrying
spools supported in rear of said work-bed, a feed-
roll effective when the platen is returned to print-
ing position, to co-operate with the platen to 25
grip the sheets preparatory to typing the page, a for-
wardly-swinging frame whereon said spools are
mounted to move forwardly with the loaded work-
sheets when said platen is rotated, said frame 30
hinged upon a support which extends down from
said carriage, the spool-frame extending upwardly
and rearwardly from its hinge and carrying
the spools at its upper end, and a regulatable
stop to determine the normal position of the 35
spool-frame.

12. In a typewriting machine, the combination
with a carriage, of a revoluble platen, means for
supporting the platen upon the carriage for dis-
placement upwardly from printing position, a
work-sheet-loading bed upon said carriage and
extending rearwardly from the platen, so that
work-sheets, deposited upon said bed when the
platen is displaced, are thereby presented face-
wise below the platen, a gage at said bed for the
leading ends of the work-sheets, a carbon-carry-
ing spool supported in rear of said work-bed and
movable forwardly with the loaded work-sheets
when the platen is rotated in line-space direc-
tion, a feed-roll effective when the platen is re-
turned to printing position, to co-operate with
the platen to grip the sheets preparatory to typ-
ing the page, and a weak spring tensioned in a
direction to return the spool rearwardly when
the platen is reversely rotated.

13. In a typewriting machine, the combination
with a carriage, of a platen, a frame for support-
ing the platen upon the carriage for displace-
ment upwardly from printing position, a work-
sheet-loading bed upon said carriage and ex-
tending rearwardly from the platen, so that work-
sheets, deposited upon said bed when the platen
is displaced, are thereby presented facewise be-
low the platen, a gage at said bed for the lead-
ing ends of the work-sheets, a carbon-supply 70
75

- supported in rear of said work-bed for forward idle movement with the loaded work-sheets when the platen is rotated, and means to co-operate with the platen, when returned to printing position, to grip the sheets preparatory to typing the page, said leading-edge gage being micrometrically adjustable to correct the position of the first printed line on the work-sheet relatively to the usual front scale upon the platen.
- 10 14. In a typewriting machine, the combination with a carriage, of a platen, a frame for supporting the platen upon the carriage for displacement upwardly from printing position, a work-sheet-loading bed upon said carriage and extending rearwardly from the platen, so that work-sheets, deposited upon said bed when the platen is displaced, are thereby presented facewise below the platen, a gage at said bed for the leading ends of the work-sheets, a carbon-supply supported in rear of said work-bed for forward idle movement with the loaded work-sheets when the platen is rotated, and means to co-operate with the platen, when returned to printing position, to grip the sheets preparatory to typing the page, said leading-edge gage being hinged upon an axis extending transversely of and below said bed and being adjustable about said axis to vary the position of the work-sheets relative to the returned platen.
- 20 15. In a typewriting machine, the combination with a carriage, of a revoluble platen, means for supporting the platen upon the carriage for displacement upwardly from printing position, a work-sheet-loading bed upon said carriage and extending rearwardly from the platen, so that work-sheets, deposited upon said bed when the platen is displaced, are thereby presented facewise below the platen, a gage for the leading ends of the work-sheets, carbon-carrying spools supported in rear of said work-bed, and a feed-roll effective when the platen is returned to printing position, to co-operate with the platen to grip the sheets preparatory to typing the page, said leading-edge gage being in advance of said feed-roll, so that the leading edges of the sheets overlie said roll when brought against said gage.
- 25 16. In a typewriting machine, the combination with a carriage, of a revoluble platen, means for supporting the platen upon the carriage for displacement upwardly from printing position, a work-sheet-loading bed upon said carriage and extending rearwardly from the platen, a gage at said bed for the leading ends of the work-sheets, carbon-carrying spools supported in rear of said work-bed, a feed-roll effective when the platen is returned to printing position, to co-operate with the platen to grip the sheets preparatory to typing the page, and a forwardly-swinging frame whereon said spools are mounted, said frame hinged upon a support which extends down from said carriage, the spool-frame extending upwardly and rearwardly from its hinge and carrying the spools at its upper end, said support hinged upon said carriage to fold forwardly in inoperative position, said spool-frame hinged to the lower edge of said support for folding forwardly therewith, and said work-bed being collapsible to an upstanding position back of the typewriting machine.
- 30 17. A work-sheet and carbon-web intercalating typewriter, having in combination a platen, an intercalating table, means to co-operate with the platen for seizing the intercalated work-sheets and carbons, and to carry them around the platen, a carbon-spool mounted to move free-

ly toward and from the platen, a spool-returning spring yielding to permit slight slack rotation of the spool, to avoid injury to the carbon by a sudden pull on the latter, and yieldable means to limit such slack rotation of the spool, 5 said spring operating to return the spool to rewind the slack carbon thereon, ready to slacken again at the succeeding jerk of the carbon, said yieldable means yielding to a stronger pull of the carbon on the spool to permit permanent 10 paying off of the carbon.

18. A work-sheet and carbon-web intercalating typewriter, having in combination a platen, an intercalating table, means to co-operate with the platen for seizing the intercalated work-sheets and carbons, and to carry them around the platen, a carbon-spool mounted to move bodily toward and from the platen, a spring yielding to permit slight slack rotation of the spool, 15 to avoid injury to the carbon by a sudden pull 20 on the latter, means to limit such slack rotation of the spool, and means for resisting further unwinding of the spool, said resisting means including a friction washer operative to permit the carbon to be pulled forcibly from the spool 25 toward the platen, said spring operating to return the spool to rewind the slack carbon thereon, ready to slacken again at the succeeding jerk 30 of the carbon.

19. A work-sheet and carbon-web intercalating typewriter, having in combination a platen, an intercalating table, means to co-operate with the platen for seizing the intercalated work-sheets and carbons, and to carry them around the platen, a carbon-spool, a spring yielding to 35 permit slight slack rotation of the spool, to avoid injury to the carbon by a sudden pull on the latter, means to limit such slack rotation of the spool, and including means for enabling the spool 40 to be further unwound at will, said spring operating to return the spool to rewind the slack carbon thereon, ready to slacken again at the succeeding jerk of the carbon, a frame whereon said spool is mounted, said frame yieldable to 45 the pull of the carbon as work-sheets and the interleaved carbon are line-spaced with the platen, and a light returning spring for said frame.

20. A work-sheet and carbon-web intercalating typewriter, having in combination a platen, an intercalating table, means to co-operate with the platen for seizing the intercalated work-sheets and carbons, and to carry them around the platen, a carbon-spool, a spring yielding to 50 permit slight slack rotation of the spool, to avoid injury to the carbon by a jerk on the latter, means to limit such slack rotation of the spool 55 and for enabling the spool to be further unwound at will, said spring operating to return the spool to rewind the slack carbon thereon, ready to slacken again at the succeeding jerk of the carbon, a frame whereon said spool is mounted, said frame yieldable to the jerk of the carbon as work-sheets and the interleaved carbon 60 are line-spaced with the platen, a light returning spring for said frame, and means adjustable for determining the normal position of said frame.

21. A work-sheet and carbon-web intercalating typewriter, having in combination a platen, an intercalating table, means to co-operate with the platen for seizing the intercalated work-sheets and carbons, and to carry them around the platen, a carbon-spool, means rotatably 70 mounting the carbon-spool, said mounting 75

means being supported for movement toward and from the platen, a spring arranged to yield and permit idle rotation of the spool, instead of bodily advance of the spool with the mounting 5 means, thereby to provide slack and hence avoid injury to the carbon by a jerk on the latter, and means to limit such idle rotation of the spool, said spring operating to return the spool to re- 10 wind the slack carbon thereon, ready to slacken again at the succeeding jerk of the carbon.

22. A work-sheet and carbon-web intercalating typewriter, having in combination a platen, an intercalating table, means to co-operate with the platen for seizing the intercalated 15 work-sheets and carbons, and to carry them around the platen, a carbon-leaf holder, a support for said holder mounted so as to be movable in opposite directions, in accordance with the line-space feed and retraction of the carbon-leaf relative to said platen, and means to prevent injury to the carbon-leaves, including 20 means resiliently connecting said carbon-leaf holder to said support, whereby a jerk upon the carbon-leaf, instead of subjecting the carbon-leaf to a tearing strain, due to the inertia of the support, results in said holder having a lim-

ited prior movement relative to said support to avoid said strain, said resilient connecting means operating to restore the holder ready to yield at a succeeding jerk of the carbon-paper.

23. In a typewriting machine, the combination with a carriage, of a revoluble platen, a sheet-gathering bed in the rear of the platen, a carbon-supply movable with the carriage and from which fly-leaves are successively movable to a position face up, and their free ends foremost, 10 on said bed in alternation with separate work-sheets, a gage for the bottom ends of the work-sheets, said gage being movable to idle position out of the path of the gathered sheets, means operable to cause said gathered sheets 15 to assume a feeding position upon the platen, and means co-operative with the revoluble platen for carrying the gathered sheets around the platen, said carbon-supply being arranged so that the carbons may advance around the 20 platen with the work-sheets during the typing, and may, after removal of the work, be retracted preparatory to gathering other sets of work-sheets.

BURNHAM C. STICKNEY. 25
